(57) **CLAIM**

The ornamental design for a dinosaur mask, as shown and described.

DESCRIPTION

FIG. 1 is a first perspective view of a dinosaur mask showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of another state of the dinosaur mask thereof.

The broken lines shown in the drawings depict portions of the dinosaur mask that form no part of the claimed design.
